Patented Apr. 3, 1962

192,522

VEHICLE LIFT

John R. Butorac, Milwaukee, Wis., assignor to Applied
Power Industries, Inc., a corporation of Wisconsin

Filed Aug. 22, 1960, Ser. No. 61,848

Term of patent 14 years

(Cl. D41—1)

FIG. 1 is a front perspective view taken from the right side of a vehicle lift embodying my new design;

FIG. 2 is a front perspective view taken from the left side thereof;

FIG. 3 is a rear view thereof taken slightly in perspective; and

FIG. 4 is a left side view thereof taken slightly in perspective.

I claim:

The ornamental design for a vehicle lift, substantially as shown.
